UNITED STATES PATENT OFFICE.

GEORGE PRIFOILD, OF SOMERVILLE, NEW JERSEY.

ART OF PRINTING RUGS.

Application filed July 24, 1926. Serial No. 124,572.

This invention relates to an improvement in the art of printing rugs, and particularly to rugs made from floor covering in strip form, and printed by means of a block printing machine before they are cut from the strip.

An object of the invention is to print more complicated designs than have heretofore customarily been used, without materially increasing the number of printing blocks required, and more particularly to provide for printing a center figure on a rug without providing additional blocks for this purpose.

In making rugs from floor covering made in a strip, such as oilcloth, linoleum and the like, it has been customary to pass a continuous strip of material through a block printing machine containing blocks which are supplied with paints of different colors, and are timed so as to print on various parts of the strip to produce the required design. The strip is thereafter cut into rugs. It is usual to provide one or two blocks for each color to print the end borders of the rugs, and one or more blocks for each color to print the side borders and fields of the rugs.

The side border and field blocks are impressed at regular intervals upon the strip between the impressions of the end-border blocks, so that the design printed between the end borders necessarily consists of the regular repetition of a figure.

According to the present invention, the monotonous regularity of a repeated figure is relieved by providing each rug with a center design. This center design is formed without the use of special blocks for the purpose, by utilizing the blocks provided for forming a part of the end-border designs of the rugs.

In order that the invention may clearly be understood, I will describe in detail specific methods embodying it, and in such description I shall refer to the accompanying drawings, in which Figs. 1 to 7 are bottom views of printing blocks, and Fig. 8 shows a part of a strip of floor covering printed from these blocks, while Figs. 9 to 11 show other printing blocks, and Fig. 12 shows part of a strip of floor covering printed from them.

I term the end-border-figure blocks. The border-figure blocks 1 to 4, impressions are made with the fill-in blocks 5 and 6. Thus block 1 bears an end-border/middle figure 1^a, and two corner figures 1^b, 1^c, each of which has the form of one-half of the middle figure 1^a.

Figure 2 shows a side border-figure block 2, which bears an end-border figure 2^a, and two corner figures 2^b, 2^c, each of which has the form of one-half of the middle figure 2^a. Figure 3 shows a middle-figure block 3, which bears a middle figure 3^a, and two corner figures 3^b, 3^c, each of which has the form of one-half of the middle figure 3^a. Figure 4 shows a block 4, which bears a middle figure 4^a, and two corner figures 4^b, 4^c, each of which has the form of one-half of the middle figure 4^a. Figure 5 shows a block 5, which bears a middle figure 5^a, and two corner figures 5^b, 5^c, each of which has the form of one-half of the middle figure 5^a. Figure 6 shows a block 6, which bears a middle figure 6^a, and two corner figures 6^b, 6^c, each of which has the form of one-half of the middle figure 6^a. Figure 7 shows a block 7, which bears a middle figure 7^a, and two corner figures 7^b, 7^c, each of which has the form of one-half of the middle figure 7^a. Figure 8 shows a strip of floor covering printed from the blocks 1 to 7, and the impressions made by the blocks 1 to 7 are registered with each other.

The blocks 5 and 6, which I term the end-border-fill-in blocks, bear figures 5^a, 5^b, 6^a, 6^b, which are positioned to print between the corner and middle figures of the blocks 1 to 4 so as to fill in the end-border designs.

The side border block shown in Fig. 7 contains figures 7^a, 7^b, 7^c and 7^d, preferably similar in form to the figures 5^a, 5^b, 6^a, 6^b, and positioned near the ends of the block to print the side borders of a rug.

In printing a series of rugs on a strip by means of the blocks which have been described, I place the blocks in a block printing machine of the construction usual in this type of work, and as the strip is moved intermittently through the machine, I manipulate the blocks in such manner as to print

upon the strip recurrent designs of the form shown in Fig. 8. In this figure, the strip is divided by dotted lines into bands A, B, C, etc., indicating the width of the printing surface of each block. Under each such band of Fig. 8 is indicated the numbers of the blocks from which impressions have been made on that band.

Adjacent impressions are made from the end-border-figure blocks 1 and 2 and 3 and 2 and 4 at regularly spaced intervals along the strip. In these adjacent impressions (shown in the bands D, E, H, A in Fig. 8), the straight or back edges 1^x, 3^x of the figures impressed by the blocks 1 and 3 are turned toward, and are preferably in contact with, the back edges 2^x, 4^x of the figures impressed by the blocks 2 and 4. In register with each

the figures of the same numbers, are what alternate pair of impressions of the end-border-figure blocks 1 to 4, impressions are made with the fill-in blocks 5 and 6. Thus

the impressions from the blocks 1 to 4 on the straight or back edges 1^x, 3^x of the figures impressed by the blocks 1 and 3 are turned toward, and are preferably in contact with, the back edges 2^x, 4^x of the figures impressed by the blocks 2 and 4. In register with each

the bands H and A', but not on the next set of impressions from the blocks 1 to 4 on the bands D and E. Between the spaced impressions of the blocks 1 to 4, (that is on the bands B, C, F, G,) impressions are made with the side-border block 7.

After the printing of the strip, the strip is cut into separate rugs along the center lines of the alternate pairs of impressions of the blocks 1 to 4 upon which the fill-in blocks 5 and 6 have also been impressed. Thus the strip shown in Fig. 8 is cut at the right-hand end of the band A and between the bands H and A'. The result of the method is that each rug is provided not only with a border, corner figures and end-border figures, but also with a center figure and side-border figures, as shown in Fig. 8.

It will be readily understood by those skilled in the art that other blocks may, if desired, be utilized to print either a solid field or a figured field on each band of the rug.

The invention may be carried out in a still more simple manner by means of the blocks shown in Figs. 9, 10 and 11. The block 9 contains a centrally-positioned symmetrical figure 9^a adapted to serve either as the center figure of a rug or as the middle figures in the end-borders of two adjacent rugs. The block 10 contains spaced figures 10^a, 10^b adapted to form the outer portions of the end-borders of two adjacent rugs. The block 11 has two figures 11^a, 11^b positioned at the ends of the block to form parts of the side-borders of the rugs.

The method of printing by means of these blocks is indicated by Fig. 12. Spaced impressions along the strip are made with the block 9, for example in the bands K, M, and K' of the strip shown in Fig. 12. In register with each alternate impression of the block 9, an impression is made with the block 10. Thus the block 10 is impressed upon the bands K, and K', but not on the band M. Impressions are made with the side-border-block 11 on all the bands between those impressed by the block 10, for example on the bands L, M and N. The strip is then cut into separate rugs along the center lines of the bands on which the block 10 has been impressed, that is on the center lines of the bands K, K'. The result of the method, as shown in Fig. 12 is to provide each rug with a border, an end-border middle figure, and also with a center figure.

From the foregoing examples of methods embodying the invention, it will be seen that by forming different parts of the end-border design on separate blocks or sets of blocks, I have made it possible to use one block, or one set of blocks, to print not only a part of the end-border but also a part or all of

a center design on each rug, and, also, if desired to print side-border middle figures on each rug. While for the sake of simplicity, I have, in the examples given, illustrated the use of only one or two colors, in practice a large number of colors are used in the border figures and center figure, a separate block being, of course, provided for each color. It is apparent that, especially if a large number of colors are used, the invention effects a material reduction in the number of blocks necessary. It has, I believe, for the first time, made it possible, as a practical matter, to print rugs with a center design in a block printing machine.

It should be clearly understood that the invention is by no means limited to printing the particular designs and figures illustrated. For the sake of illustration, simple geometrical figures have been used, but in carrying out the invention the figures of the design may be as complicated as desired and may be of any decorative or pictorial form.

What is claimed is:

1. The improvement in the art of printing rugs, which comprises forming parts of end-border designs on separate blocks or separate sets of blocks, utilizing both said blocks or both said sets of blocks to print end-border designs on each rug, and utilizing one of said blocks or one set of said blocks to print a design at an intermediate part of each rug.

2. The improvement in the art of printing rugs, which comprises forming the middle and corner portions of end-border designs, and the intermediate portions thereof, on separate blocks; and utilizing the first of said blocks to print on each rug a center figure and side-border figures, as well as to print parts of the end-border.

3. The improvement in the art of printing rugs, which comprises forming the middle and outer portions of end-border designs on separate blocks, and utilizing the first of said blocks to print on each rug a center figure, as well as to print a part of the end-border.

4. The method of making printed rugs from strip material, which comprises printing a pair of adjacent end-border middle figures at intervals along the strip, printing the remainder of a pair of end-border designs in register with each alternate pair of middle figures, cutting the strip into separate rugs on the center lines of said pairs of middle figures, so that the other alternate pairs of middle figures provide a center figure in each rug.

5. The method of making printed rugs from strip material, which comprises printing a pair of adjacent end corner figures at intervals along the strip, printing in the remainder of a pair of end-border designs in register with each alternate pair of end-cor-

ner figures, cutting the strip into separate rugs on the center lines of said pairs of end-corner figures, so that the other alternate pairs of end-corner figures provide side-
5 border middle figures in each rug.

6. The method of making printed rugs from strip material, which comprises printing pairs of adjacent end-border middle figures and corner figures at intervals along
10 the strip; printing in the remainder of a pair of end-border designs in register with each alternate pair of said corner and middle figures, cutting the strip into separate rugs on the center lines of said pairs, so that the
15 other alternate pairs of middle figures and corner figures provide a center figure and a side-border figure in each rug.

7. The method of printing rug designs on a strip, which comprises making spaced im-
20 pressions with blocks providing an end bor-
der middle design, completing the end border on alternate sets of impressions on said blocks, while utilizing the other impressions
thereof as a center design.

8. The improvement in the art of printing 25
rugs on a long strip of material, which con-
sists in providing blocks having oppositely
turned middle designs, and utilizing said
blocks to print an end-border middle figure
at each end of each rug and a center figure 30
on each rug.

9. A block for use in printing rug designs on a strip of material, having a middle bor-
der figure and two corner figures of which
the lower one corresponds to the upper half 35
of the middle figure and the upper one to
the lower half of the middle figure.

10. Two blocks for use in a block printing
machine for printing rug designs on a strip
of material, of which one has a symmetrical 40
figure at its middle, and the other has spaced
symmetrical figures at its ends arranged to
cooperate with the middle figure of the first
block in forming end-border designs at the
45 adjacent ends of each two rugs.

In testimony whereof I have hereunto set
my hand.

GEORGE PRIFOLD.
